United States Patent Office

Des. 187,711
Patented Apr. 19, 1960

187,711

STOCKING

Max Fisher, Lower Alsace Township, Berks County, Pa.

Application January 20, 1958, Serial No. 49,305

Term of patent 14 years

(CL. D47—7)

Figure 1 is a rear perspective view of the lower portion of the stocking showing my new design; and

I claim:
The ornamental design for a stocking, as shown.
